UNITED STATES PATENT OFFICE

HOMER F. LIVERMORE, OF BROOKLINE, MASSACHUSETTS, ASSIGNOR TO GUARANTEED PARTS, INC., OF ALLSTON, MASSACHUSETTS, A CORPORATION OF MASSACHUSETTS

HARNESS CORD FOR LOOMS

Application filed January 9, 1931. Serial No. 507,606.

This invention relates to an improved harness cord for looms, sometimes known as a dobby cord, said harness cord being well known to those skilled in the art and employed to connect the top of the harness to the harness lever.

The object of the invention is to provide a harness cord which is strong and very durable.

The invention consists in a harness cord for looms of the character set forth in the following specification and particularly pointed out in the claims.

Referring to the drawings:

Fig. 1 is a front elevation of a harness cord embodying my invention.

Fig. 2 is a plan view of the same, Figs. 1 and 2 being broken away.

Fig. 3 is a transverse section taken on the line 3—3 of Fig. 1.

Fig. 4 is a sectional elevation taken on the line 4—4, Fig. 1.

Fig. 5 is a sectional elevation taken on line 5—5, Fig. 2.

Like numerals refer to like parts in the several views of the drawings, which are made on an enlarged scale.

In the drawings, 6 is a core embodying a core 7 of flexible wire, preferably the said core is made up of a plurality of strands of flexible wire forming as a whole the core 7 of the harness cord. The core 7 is covered with a covering of textile material 8. One end of the flexible wire core 7, as seen at the left of Figs. 1 and 5, terminates in a circular portion 9, and the said circular portion is surrounded by a tubular annular portion 10 of a clamp 11.

The annular portion 10 has a hollow ferrule 12 integral therewith and projecting radially therefrom and embracing that portion 13 of the cord 8 which is adjacent to the circular portion 9 thereof, the ferrule being clamped to the cord. That portion of the cord which is positioned within the tubular annular portion of the clamp 11 has the covering 8 removed therefrom. The tubular annular portion 10 of the clamp 11 is fastened to the circular portion 9 of the core by solder

15 so that the circular portion 9 cannot slip in the hollow annular portion 10.

The right hand end of the harness cord terminates in a hook 16 which in construction is the same as the left hand end, Figs. 1 and 5, except that there is a space 17 provided in the annular portion of the clamp 11' through which the link 18 shown in dotted lines in Figs. 1 and 2 may be introduced. If the link 18 is attached to the hook 16, the hook may be compressed to narrow the space 17, so that the link cannot become accidentally detached from the hook.

I claim:

1. A harness cord for looms embodying a core of flexible wire, the end of said wire terminating in a circular portion and a clamp embodying a hollow annular portion and a ferrule integral therewith and projecting radially therefrom, said circular portion of the cord being positioned within the hollow annular portion of said clamp and soldered thereto, the ferrule embracing that portion of the cord adjacent said circular portion.

2. A harness cord for looms embodying a core of flexible wire, the end of said wire terminating in a circular portion and a clamp embodying a tubular annular portion and a split ferrule integral therewith and projecting radially therefrom, said circular portion of the cord being positioned within and surrounded by the tubular annular portion of said clamp, the ferrule embracing that portion of the cord adjacent said circular portion and clamped and soldered thereto.

3. A harness cord for looms embodying a core of flexible wire, the end of said wire terminating in a circular portion and a clamp embodying a ferrule embracing that portion of the cord adjacent said circular portion, and a tubular metal eye on one end of the ferrule integral therewith and embracing said circular portion of the cord and soldered thereto.

4. A harness cord for looms embodying a core of flexible wire and a covering of textile material thereon, the end of said wire projecting beyond its covering and terminating in an arcuate portion, and a clamp embodying a tubular annular portion and a ferrule

integral therewith and projecting radially therefrom, said arcuate portion of the core being positioned within the hollow annular portion of said clamp and soldered thereto, 5 the ferrule embracing that portion of the cord adjacent said arcuate portion.

In testimony whereof I have hereunto set my hand.

HOMER F. LIVERMORE.
